CLAIM

I claim the ornamental design for a piddle pole, as shown and described.

DESCRIPTION

FIG. 1 shows a top and side perspective view of the piddle pole.

FIG. 2 shows a bottom and side perspective view thereof.

FIG. 3 shows a first elevation view of the piddle pole, the opposite side being a mirror image thereof.

FIG. 4 shows a second elevation view of the piddle pole, the opposite side being a mirror image thereof.

FIG. 5 shows a third elevation view thereof, 90 degrees rotated with respect to the views of FIGS. 3 and 4.

FIG. 6 shows a top plan view thereof; and,

FIG. 7 shows a bottom plan view thereof.

1 Claim, 6 Drawing Sheets# US D864,502 S
